UNITED STATES PATENT OFFICE.

ALBERT L. BUCHER, OF NORTH BALTIMORE, OHIO.

VEHICLE-RACK.

SPECIFICATION forming part of Letters Patent No. 636,949, dated November 14, 1899.

Application filed August 28, 1899. Serial No. 728,749. (No model.)

To all whom it may concern:

Be it known that I, ALBERT L. BUCHER, a citizen of the United States, residing at North Baltimore, in the county of Wood and State 5 of Ohio, have invented a new and useful Vehicle-Rack, of which the following is a specification.

My present invention relates to vehicle-racks of that class designated "combination to wagon-racks," which employed as an attachment for farm or other wagons are designed to adapt the latter for the accommodation of freight of varying form and bulk.

The object of the invention is to produce a 15 simple, readily-detachable, and easily-adjustable rack designed in its various positions to accommodate hay, wood, grain, and various other classes of load.

In its specific aspect the invention consists 20 in the novel construction hereinafter described and illustrated, and succinctly pointed out in the appended claim.

Referring to the drawings, Figure 1 is a perspective view of a wagon body or platform 25 provided with my rack, the side racks being shown in their two intermediate adjustments for the purpose of illustrating the manner in which the rack is adapted for the accommodation of stick-wood. Fig. 2 is a side view 30 of the same, showing the racks in their elevated positions. Fig. 3 is an end view showing the racks in their depressed positions for the accommodation of hay. Fig. 4 is a detail view in perspective of one of the keepers 35 and the connected parts of the structure, and Fig. 5 is a detail view in perspective of one of the spring-stirrups designed for the adjustable retention and support of the links.

Referring to the numerals of reference on 40 the drawings, 1 indicates the wagon-platform, designed to be supported upon running-gear in the ordinary manner and provided with side rails 2.

3 and 4 indicate head or end racks, preferably, though not necessarily, bolted at their lower ends between the rails 2 at the opposite ends of the wagon and comprising the side pieces 5 and 6 and one or more cross-pieces 7.

8 indicates an end brace extending between 45 the extremities of the rails 2 immediately beyond the end frames 3 and 4, serving to brace

the rails and to aid in the support of the end frames, which, as illustrated, are in divergent relation.

9 9 indicate extensible sections of the end 55 frames, the preferred manner of mounting them being by way of hinges 10, intermediate of the contiguous ends of the end frames and their extensions and located along one edge in order that the contiguous end faces of the 60 side bars will be correlative when the extensible sections are swung upwardly into alignment with the end frames, as shown in dotted lines in Fig. 1, and there secured by means of catches 11, located opposite the hinges. 65

12 12 indicate the side racks, comprising a series of standards 13, united by a series of horizontal rack-bars 14 and hinged at their lower ends by means of ordinary slip-pintle hinges 15 to the rails 2. It will now be seen 70 that by means of this hinged connection between the side racks and the rails of the wagon-body the former may be swung to any desired position, and I shall now proceed to a description of novel supporting and adjust- 75 ing mechanism which I have devised for readily arranging the racks in the several positions illustrated for the accommodation of the various materials to be hauled.

16 16, &c., indicate a series of keepers located, respectively, upon each of the standards 13 of the racks 12, preferably about midway of their length, and accommodating one end of supporting and adjusting links 17, the other ends of which when the racks are in 80 place upon the wagon are slipped into and retained by what may be termed "spring-stirrups" 18, opening upwardly, as illustrated, and secured to the rails directly below the hinges 15. If a single inclined adjustment is re- 85 quired—as, for instance, the lowest position—the adjusting means described thus far will be found sufficient; but if a series of inclinations of the side racks is desirable one or more notches or rests 19 may be formed in 90 the standards 13 within the keepers. In this event the racks may be retained in any position from the vertical (at which time the rack is retained against the sides of the end frames by catches 20, the upper end of the links ly- 95 ing at the lower ends of the keepers) to the almost horizontal position for the accommo- 100

dation of hay, at which time the upper ends of the links are situated at the upper extremities of the keepers, serving to brace the racks.

The spring-stirrups 18 permit the links to

- 5 swing freely to accommodate themselves to various positions of the racks, and when it is desired to remove the racks entirely from the vehicle it is simply necessary to slip the pintles of the hinges 15 and draw the lower ends
- 10 of the links from the stirrups, slightly more than casual force being required for the latter purpose, as it is intended that the inturned extremities 21 of the free or outer side of the stirrup shall in some measure resist the casual
- 15 displacement of the link, without, however, opposing material resistance to the detachment of the parts when it is desired to use the vehicle without the rack.

The embodiment of my invention illustrated

- 20 and described appears at this time preferable; but I do not desire to limit myself to the struc-

tural details enumerated, as it is obvious that they are susceptible of change, modification, and variation within the scope of the protection prayed.

25

What I claim is—

In a vehicle-rack, the combination with a support, of a rack detachably hinged thereto and provided with a keeper and a series of rests within the keeper, a link movable within 30 the keeper and designed to engage the rests to adjustably retain the rack, and a spring-stirrup carried by the support, provided with an inturned end and designed to detachably retain the lower end of the link.

35

In testimony that I claim the foregoing as my own I have hereto affixed my signature in the presence of two witnesses.

ALBERT L. BUCHER.

Witnesses:

GEO. W. EWING,
J. F. WOOD.
